UNITED STATES PATENT OFFICE.

JOHN MAUSER, OF NEW YORK, N. Y.

BARREL-REGISTER.

SPECIFICATION forming part of Letters Patent No. 703,733, dated July 1, 1902.

Application filed January 16, 1902. Serial No. 90,001. (No model.)

To all whom it may concern:

Be it known that I, JOHN MAUSER, residing in New York, borough of Bronx, and State of New York, have invented certain new and 5 useful Improvements in Barrel-Registers, of which the following is a specification.

This invention relates to certain improvements in the machine for registering barrels for which Letters Patent No. 268,926, dated 10 December 12, 1882, were granted to C. M. Müller and myself as joint inventors, and which is intended to be used in breweries for counting and registering the kegs or barrels according to their size, in the course of shipping the same.

The invention is intended to be used for registering various standard sizes of barrels—such as one-half, one-quarter, and one-sixth barrels—as they are conveyed past the apparatus; and for this purpose the invention consists of a barrel-register which comprises a suitable bed, an inclined supporting-frame secured thereto, a registering-indicator mounted at one side of the inclined supporting-frame, a swinging and counterbalanced lever provided with a roller and which is actuated by the barrels that are passed on a suitably-provided way below the machine and in contact with the roller, an oscillating frame connected with said counterbalanced lever and having a partially circumferential surface, projections provided thereon, pivoted and spring-actuated latches, means for connecting said spring-actuated latches with the registering-indicator, a slide-frame provided on the inclined supporting-frame and operated simultaneously with the oscillating frame, a notched side plate secured thereto, a fulcrumed and spring-actuated pawl arranged 25 on said slide-frame and adapted to engage said notched side plate, and means for releasing said fulcrumed pawl at the end of the return motion of the oscillating frame after the registering-indicator has been actuated to 30 register the barrel that has raised the oscillating frame in passing the machine; and the invention consists, further, of certain details of construction and combinations of parts which will be fully described hereinafter and 35 finally pointed out in the claims.

In the accompanying drawings, Figure 1 is a side elevation of my improved machine for

counting barrels, showing the same in its normal position ready for use. Fig. 2 is an end elevation of the same. Figs. 3 and 4 are 55 elevations, partly in section, on line 3 3, Fig. 1, showing the parts in two different positions; and Figs. 5 and 6 are details showing the connection of the sector-shaped frame, with the slide-frame in its normal and shifted 60 positions, respectively.

Similar letters of reference indicate corresponding parts.

Referring to the drawings, A represents the bed of my improved machine for registering 65 barrels and consists of the parallel beams A' and the plate A². The bed is arranged in operative relation with any suitable way, conveyor, or elevator for the barrels, so that the barrels in passing the apparatus actuate the 70 same and are registered according to their sizes. Upon the plate A² is mounted securely an inclined supporting-frame B, that is provided with a registering-indicator C, arranged at a side edge thereof, a slide-frame D upon 75 its upper inclined face, and an oscillating frame E, supported from the under side and adapted to operate in vertical oscillating motion through the rectangular opening thereof. To the under side of the beams A' is 80 pivotally arranged a swinging lever F, which carries a roller F' at its free end and which is supported by the rod f from the lower end of the oscillating frame E. An air-cush- 85 ion device G is arranged upon the plate A² of the bed of the machine and has a piston-rod g pivotally connected with the upper leg of the oscillating frame E. The oscillating frame E is secured on a pivotal shaft E', which has suitable bearings on the under side 90 of the inclined supporting-frame B. An arc-plate E² is connected with the radial legs of the oscillating frame E and is provided with longitudinal slots e, that are arranged in vertically-different planes, one above the other, 95 in which are adjustably secured projections e' e² e³. These projections vary in length from the longest at the bottom to the shortest at the top. The upper radial leg of the oscillating frame E is provided with a pivotal 100 connection e⁴ for the piston-rod G of the air-cushion device, which device is pivotally mounted upon suitable standards, so that it will follow the motion of the slide-frame D

and which serves to take up the shocks that are exerted by the barrels as they actuate the apparatus and also permit a slow return of the oscillating frame E and the lever F to their normal positions after they have been raised by the barrels. On the upper face of the inclined supporting-frame B is guided the slide-frame D, that has at its upper end a guide-plate D', which has at its ends the longitudinal slots d, arranged to be guided along the headed studs d', as shown in Figs. 3 and 4. The lower end of the slide-frame D is guided on a stationary center pin d³, that is secured in the lug d⁴ on the lower end of the inclined supporting-frame B, as shown in Figs. 3 and 6. The guide-plate D' is provided with ears d² adjacent its ends that carry a pivotal shaft L, on which are pivoted and suitably spaced apart to lie in planes corresponding to the projections on the arc-plate of the oscillating frame E spring-actuated latches l' l² l³. These spring-actuated latches l' l² l³ are connected with the arms c of the registering-indicator C by the rods c' c² c³, respectively.

The transverse shaft E', to which the oscillating frame E is fulcrumed, is provided at one end with a projecting cam i, which engages a downwardly-extending arm i', attached to the adjacent side of the slide-frame D, so that when the oscillating frame E is moved in upward direction the cam i engages the arm i' and moves thereby the slide-frame D in upward direction on the inclined supporting-frame B.

Fulcrumed on the upper face of the inclined supporting-frame B at one side of the slide-frame D is a spring-actuated pawl p, which is provided with a curved lower end p', that is adapted to be engaged by the projecting pin i², secured on the pivotal shaft E' adjacent the cam i. The upper end of the pawl p is provided with a spring p², that serves to keep the end of the pawl in contact with the notched plate p³, carried on the adjacent side of the slide-frame D. Simultaneously with the oscillations of the oscillating frame E the cam i causes the slide-frame D to move by wiping against the depending arm i'. The slide-frame D will be moved in upward direction to a greater or less extent, according to the various sizes of barrels that raise the swinging lever F and the oscillating frame E, and the upper end of the spring-actuated pawl is adapted to engage the notched plate p³ in order to support the slide-frame in outward position until the oscillating frame E is lowered sufficiently to carry the projecting pin i' into engagement with the curved end p' of the pawl, so as to disengage the same from the notched plate p³ and allow the slide-frame D to return to its normal position under the action of its own weight. The projections e' e² e³ on the oscillating frame E are raised to the height of the latches l' l² l³, respectively, as barrels of one-sixth, one-quarter, and one-half sizes actuate the apparatus. In the full sweep of the oscillating frame E, as when ac-

tuated by a half-size barrel, the slide-frame D is moved upwardly to its limit and the spring-actuated pawl p, engaging the notched plate p³, retains it in such position. The projection e' being the longest, it is adapted to engage its respective latch l³, while the slide-frame is retained in raised position, and the other latches l' l² are maintained out of the path of the projections e' e² by reason of the same being shorter than the projection e³, so that upon the return motion of the oscillating frame the projection e³ will engage its respective latch l³ and actuate the registering-indicator C. The slide-frame D is retained in this position until the oscillating frame E has returned to the point where the projection e' has passed below the latches, when the projecting pin i disengages the spring-actuated pawl and the return of the slide-frame takes place, so that the latches l' l² cannot engage with the projections e' e² when the device is actuated by a half-size barrel. When a one-quarter-size barrel actuates the apparatus, the oscillating frame E is raised to the height where the projection e² reaches its respective latch l², and the slide-frame D is moved in upward direction far enough for the latch l' to be retained out of the path of the projection e', and upon the return of the oscillating frame the projection e² will engage the latch l², thereby actuating the registering-indicator, and so when a one-sixth-size barrel actuates the apparatus the projection e' will engage with its respective latch l' and cause the actuation of the registering-indicator with but a slight movement of the slide-frame, which is insufficient to cause the spring-actuated pawl to engage with the notched plate. It will be seen, therefore, that by a full sweep of the oscillating frame, as when actuated by a one-half-size barrel, the slide-frame moves upwardly to its limit and is retained in such position, so that upon the return of the oscillating frame the projection e³, which is the longest, is the only one that will engage with its latch, while the others pass their respective latches without engaging therewith; also, when a one-quarter-size barrel actuates the device the slide-frame is moved sufficiently that the projection e' cannot engage with its latch l' and only the projection e² engages its latch; but when a one-sixth-size barrel actuates the device the slide-frame has but a slight movement, as the oscillating frame is raised only high enough for the projection e' to engage its latch l' and does not, therefore, cause the cam i to operate the slide-frame. By this construction it will be apparent that barrels of various sizes can be accurately and reliably registered.

Having thus described my invention, I claim as new and desire to secure by Letters Patent—

1. In a barrel-register, the combination, with an inclined supporting-frame secured to a suitable bed, of a registering-indicator, an oscillating frame, means for actuating said

oscillating frame, means provided on said inclined supporting-frame for actuating said registering-indicator, and means on said oscillating frame for operating said registering-indicator-actuating means, substantially as set forth.

2. In a barrel-register, the combination, with an inclined supporting-frame secured to a suitable bed, of a registering-indicator, an oscillating frame, a swinging lever connected at its free end with said oscillating frame, means provided on said inclined supporting-frame for actuating said registering-indicator, and means on said oscillating frame for operating said actuating means, substantially as set forth.

3. In a barrel-register, the combination, with an inclined supporting-frame secured to a suitable bed, of a registering-indicator, an oscillating frame, a swinging lever pivotally secured to said bed and having an antifriction-roller mounted at its free end, means connecting said free end thereof with said oscillating frame, means provided on said inclined supporting-frame for actuating said registering-indicator, and means on said oscillating frame for operating said actuating means, substantially as set forth.

4. In a barrel-register, the combination, with an inclined supporting-frame secured to a suitable bed, of a registering-indicator, an oscillating frame, a swinging lever having its free end connected with said oscillating frame, spring-latches provided on said inclined supporting-frame, means connecting said latches with said registering-indicator, and means provided on said oscillating frame for operating said spring-latches, substantially as set forth.

40 5. In a barrel-register, the combination, with an inclined supporting-frame secured to a suitable bed, of a registering-indicator, an oscillating frame, a swinging lever connected at its free end with said oscillating frame, latches pivotally mounted on said inclined supporting-frame, means connecting said latches with said registering-indicator, and projections provided on said oscillating frame to engage said latches, substantially as set forth.

50 6. In a barrel-register, the combination, with an inclined supporting-frame secured to a suitable bed, of a registering-indicator, an oscillating frame, a swinging lever connected at its free end with said oscillating frame, latches pivotally mounted on said inclined supporting-frame and arranged suitably spaced apart, means connecting said latches with said registering-indicator, and projections provided on said oscillating frame, being arranged in separate planes corresponding with said latches, substantially as set forth.

65 7. In a barrel-register, the combination, with an inclined supporting-frame secured to a suitable bed, of a registering-indicator, an oscillating frame, a lever pivoted to said bed and being connected with said oscillating

frame, a slide-frame guided on said inclined supporting-frame, latches mounted on said slide-frame, means for sliding said slide-frame, and projections on said oscillating frame arranged in corresponding planes with said latches, substantially as set forth.

8. In a barrel-register, the combination, with an inclined supporting-frame secured to a suitable bed, of a registering-indicator, an oscillating frame, a lever for actuating said oscillating frame, a slide-frame guided on said inclined supporting-frame, latches pivotally mounted on said slide-frame and being arranged horizontally spaced apart, means for sliding said slide-frame on said inclined supporting-frame, and adjustable projections of different lengths arranged on said oscillating frame in corresponding vertical planes with said latches, substantially as set forth.

9. In a barrel-register, the combination, with an inclined supporting-frame secured to a suitable bed, of an oscillating frame having an arc-plate, a pivotal shaft provided on the underside of said inclined supporting-frame, said oscillating frame rigidly mounted thereon, a registering-indicator secured to said inclined supporting-frame, an air-cushion device supported on said bed and being connected with said oscillating frame, a swinging lever for actuating said oscillating frame, a slide-frame guided on said inclined supporting-frame, a pivotal shaft provided at the upper end of said slide-frame, latches mounted and spaced apart on said pivotal shaft of the slide-frame, means for operating said slide-frame, means connecting said latches with said registering-indicator, and adjustable projections of different lengths secured on said arc-plate of the oscillating frame, being arranged in vertical planes of said latches, substantially as set forth.

10. In a barrel-register, the combination, with an inclined supporting-frame, secured to a suitable bed, of an oscillating frame, a pivoted shaft for said oscillating frame, a slide-frame guided on said inclined supporting-frame, a depending finger on said slide-frame, and a cam provided on said pivoted shaft adapted to coöperate with said depending finger simultaneously with the motion of the oscillating frame, substantially as set forth.

11. In a barrel-register, the combination, with an inclined supporting-frame, of an oscillating frame, a pivotal shaft journaled at the under side of said inclined supporting-frame, said oscillating frame mounted thereon, a slide-frame guided on said inclined supporting-frame, a finger depending from one side thereof, a cam on said pivotal shaft adapted to engage the same, a spring-actuated pawl mounted adjacent one side of the slide-frame, a notched plate on said slide-frame, and means for actuating said pawl, substantially as set forth.

12. In a barrel-register, the combination, with an inclined supporting-frame, of an os-

cillating frame, a pivotal shaft journaled at the under side of said inclined supporting-frame, said oscillating frame mounted thereon, a slide-frame guided on said inclined supporting-frame, a finger depending from one side thereof, a cam on said pivotal shaft adapted to engage the same, a spring-actuated pawl having a curved end and being mounted on said inclined supporting-frame adjacent said slide-frame, a notched plate provided on said slide-frame for said pawl,

and a pin on said pivotal shaft adapted to engage said curved end of the spring-actuated pawl, substantially as set forth.

In testimony that I claim the foregoing as 15 my invention I have signed my name in presence of two subscribing witnesses.

JOHN MAUSER.
